CLAIM

The ornamental design for a base for a cooking pot or the like, as shown and described.

DESCRIPTION

FIG. 1 is a top front perspective view of a base for a cooking pot or the like, showing my new design;

FIG. 2 is a top plan view thereof;

FIG. 3 is a side elevational view thereof;

FIG. 4 is a bottom plan view thereof;

FIG. 5 is a cross-sectional view thereof taken on line 5—5 of FIG. 2; and

FIG. 6 is a bottom perspective view thereof with the cooking pot shown in broken lines for illustrative purposes only.

FIG. 1

FIG. 2

FIG. 3

FIG. 4

FIG. 5

FIG. 6
